US0D1050480S

(12) **United States Design Patent** (10) Patent No.: **US D1,050,480 S**
(45) Date of Patent: ** Nov. 5, 2024

(54) **MEDICAL INSTRUMENT**

(71) Applicant: **Innoventa Medica ApS**, Birkerød (DK)

CN 304554777 * 3/2018

(72) Inventor: **Niels Erik Holm**, Birkerød (DK)

CN 307312159 * 5/2022

CN 308568864 * 4/2024

(**) Term: **15 Years**

(21) Appl. No.: **35/518,100**

(22) Filed: **Jul. 27, 2023**

(80) **Hague Agreement Data**

Int. Filing Date: **Jul. 27, 2023**

Int. Reg. No.: **DM/230726**

Int. Reg. Date: **Jul. 27, 2023**

Int. Reg. Pub. Date: **Aug. 18, 2023**
